UNITED STATES PATENT OFFICE.

HUBERT A. LEISE, OF MERIDEN, CONNECTICUT.

TELEPHONE INSTRUMENT.

1,394,563.

Specification of Letters Patent. Patented Oct. 25, 1921.

Application filed May 27, 1920. Serial No. 384,722.

To all whom it may concern:

Be it known that I, HUBERT A. LEISE, a citizen of the United States, residing at Meriden, in the county of New Haven and State of Connecticut, have invented a new and useful Improvement in Telephone Instruments; and I do hereby declare the following, when taken in connection with the accompanying drawings and the characters of reference marked thereon, to be a full, clear, and exact description of the same, and which said drawings constitute part of this application, and represent, in—

Figure 1, a side view, partly in section, of a telephone receiver constructed in accordance with my invention.

Fig. 2, an inside view of the receiver-shell detached.

This invention relates to an improvement in telephone instruments and particularly to telephone receivers and transmitters. In telephone receivers and transmitters, as at present constructed, the diaphragm is seated upon the edge of a chamber forming a tight air-space which interferes with the proper vibration of the diaphragm. The object of this invention is to vent this chamber so as to permit the diaphragm to vibrate freely; and the invention consists in the construction as hereinafter described and particularly recited in the claim.

As shown in Fig. 1 of the drawings, I have illustrated my invention as applied to a receiver 5 including a metal receiver-shell 6 having a flange 7 which rests upon the edge 8 providing a bearing for the diaphragm 9, which is held against the shell by the usual cap 10. My present improvement consists in forming this receiver-shell with a series of notches 11, more or less in number, and herein shown in Fig. 2 as having three notches. These notches being formed inside the inner face of the diaphragm, permit the circulation of air so that the diaphragm is free to vibrate under the action of the magnets.

I claim:

A telephone instrument including a casting, a diaphragm-supporting shell mounted therein and formed in its outer edge with a flange and with a notch opening through said flange, a single disk diaphragm resting upon the said flange and closing the open end of said notch.

In testimony whereof, I have signed this specification in the presence of two subscribing witnesses.

HUBERT A. LEISE.

Witnesses:

WILLIAM C. SWEENEY,
RICHARD HENRY BOURNE.
